United States Patent Office

Des. 218,859
Patented Sept. 29, 1970

218,859

OUTRIGGER CANOE

Fred J. Gallagher, 704 E. Thompson St.,
Princeton, Ill. 61356

Filed July 17, 1969, Ser. No. 18,247

Term of patent 14 years

Int. Cl. D12—06

U.S. Cl. D71—1

Fig. 2

Fig. 1

Fig. 3

FIG. 1 is a top perspective view of an outrigger canoe embodying my design;

FIG. 2 is a view of the right side of the canoe, the left side (not shown) being substantially a mirror image of that shown;

FIG. 3 is a front elevational view of the bow of the canoe, the stern elevational view being substantially identical;

FIG. 4 is a top plan view; and

FIG. 5 is a view of the bottom thereof.

I claim:

The ornamental design for an outrigger canoe, as shown and described.
